UNITED STATES PATENT OFFICE.

ARTHUR J. WIDMER, OF WEBSTER GROVES, MISSOURI, ASSIGNOR TO WIDMER ENGINEERING COMPANY, OF ST. LOUIS, MISSOURI, A CORPORATION OF MISSOURI.

APPARATUS FOR CONSTRUCTING FLOORS

1,291,325.

Specification of Letters Patent. Patented Jan. 14, 1919

Application filed February 21, 1917. Serial No. 150,019.

To all whom it may concern:

Be it known that I, ARTHUR J. WIDMER, a citizen of the United States, and a resident

of Webster Groves, in the county of St. Louis and State of Missouri, have invented a new and useful Improvement in Apparatus for Constructing Floors, of which the following is a specification. Referring to the drawings, the concrete floor slab 15 has parallel strengthening ribs 16 on its under side. The forms for supporting the concrete while it is setting are supported directly upon adjustable blocks 17.

65 Following is a specification to 10 forms and centering for constructing ribbed, spaced, about four or more feet apart, 15 concrete floors, of buildings of one or more stories, in height, and other buildings where the length of the steel pans or other floor forms 20 in it is desired to use the same forms repeatedly, are resculpted which the floor is molded. The joists 25 are held up by posts 18 at suitable intervals.

15. The objects of the invention are to save labor, to increase the number in the centering, to permit the metal to be used repeatedly, to provide iron floor pans to be used repeatedly, to provide, in Figs. 1 to 4, the soft forms 19 are steel for the rapid centering, the floor pans 20 are made of iron.

for the rapid erection and the easy removal of channels, which are laid down on the joists of the centering and forms, and to adapt them parallel to each other at a distance apart of 75 same sizes of floor pans to constructing variations about two feet or more for supporting the different sizes of floors.

ous sizes of doors, not exceeding 10' x 16'. The sides of the ribs and the under part of the floor slab are supported by inclined jacks which support the floor inverted trough shape steel forms, or pans 20 forming crosswise of the direction of the floor slab.

25 forms crosswise of the direction in which the floor ribs extend; and in arranging suitably shaped soft forms and floor forms crosswise of the joists in alternation and spaced apart to conform to the spacing of the ribs. which are arranged between the soft forms 19 extending in the direction of their length. The pans are four feet or so long, and are butted together or lapped at their ends over the joists. 80

The soffit forms rest directly upon the joists, Blocks 24 are arranged on the joists between the soffit forms 19 for supporting the 30 and the floor forms are spaced above the joists and supported on the edges of the soffit forms 19 for supporting the ends of the floor forms above the joists. The

fits upon blocks or strips which rest upon the joists, so that the supports for the floor forms may be removed and the floor forms

35 may be lowered without disturbing the soft joists, or they may butt together at their ends. By removing the blocks ²¹ the floor forms ²⁰ may be dropped down at their

40. *Fig. 1.*—The ends are described below, reference being had to the accompanying drawings forming a part of this specification, which show the invention.

the invention in several forms; and what is removed after the concrete has set two or claimed as the invention is set forth in the three days. The soffit forms 19 and joists appended claims and posts may be left in place until the floor

In the drawings, wherein the same reference characters designate the same or similar parts in the several views, has hardened and is self-supporting, as shown in Fig. 1. The invention is not restricted to the par-

Figure 1 is a plan view of the forms for a portion of a floor, the floor pans being partly removed to disclose the arrangement of the particular shapes of forms shown in the drawings, div. I claim the following as my invention:

Fig. 2 is a vertical sectional view of the same on the line 2-2 in Fig. 1.

Fig. 3 is a cross-section of the completed floor, on the line 3-3 in Fig. 1, showing all 55 of the forms in place.

Fig. 4 is a view similar to Fig. 3, showing the effect of the same conditions as in Fig. 3, but with the beam length increased to 100 cm.

joists, and removable means for supporting said floor forms above the level of said joists, the space between said floors forms and joists being sufficient to permit alining sections to be telescoped one within the next to withdraw their ends from over said joists whereby said forms can be lowered between the joists.

2. Apparatus for constructing concrete floors comprising joists, continuous forms supported on said joists and projecting above them, sectional forms arranged between said continuous forms, the ends of successive sectional forms overlapping each other at the joists, and removable means for supporting said sectional forms above the level of said joists, the space between said sectional forms and joists being sufficient to permit alining sections to be slid lengthwise one under the next to withdraw their ends from over said joists whereby said forms can be lowered between the joists.

3. Apparatus for constructing ribbed concrete floors comprising a continuous supporting member extending crosswise of the ribs beneath their under sides for supporting them, floor forms projecting above said supporting member and having portions extending between the ribs, the ends of successive floor forms meeting above said supporting member, and means carried by said supporting member for supporting said floor forms above the level of said supporting member, said form supporting means being removable independently of said supporting member to permit the forms to be lowered without disturbing the supporting member.

4. Apparatus for constructing ribbed concrete floors comprising a continuous supporting member extending crosswise of the ribs, soffit forms extending across said supporting member in alinement with said ribs beneath their under sides for supporting them, floor forms arranged between said soffit forms and projecting above them between the ribs, the ends of said floor forms overlapping each other above said supporting member, and means carried by said supporting member for supporting said floor forms, said form supporting means being removable independently of said supporting member to permit the forms to be lowered without disturbing the supporting member.

5. Apparatus for constructing ribbed concrete floors comprising joists extending crosswise of the ribs, supports for the ribs, sectional forms supporting the floor between the ribs, said sectional forms having their ends free of the joists, and means for supporting said sectional forms above the joists, said supporting means being removable to permit the lowering of said sectional forms

between the supports for the ribs and independently of said joists.

6. Apparatus for constructing ribbed concrete floors comprising joists extending crosswise of the ribs for supporting them at intervals, sectional forms supporting the floor between the joists, said sectional forms having their ends lapped immediately over the joists, and supports for the lapped ends of said forms, said supports being supported on said joists in the spaces between the ribs and being removable to permit the lowering of said sectional forms independently of said joists.

7. Apparatus for constructing ribbed concrete floors comprising joists extending crosswise of the ribs, soffit forms arranged crosswise upon said joists and supporting said ribs, sectional forms supporting the floor between the ribs, said sectional forms having their ends spaced above and free of the joists, and means carried by said joists for supporting said sectional forms above the level of the joists, said supporting means being arranged in the spaces between the ribs and being movable to permit the lowering of said sectional forms independently of said joists.

8. Apparatus for constructing ribbed concrete floors comprising joists extending crosswise of the ribs, soffit forms extending across said joists lengthwise of said ribs for supporting their under sides, collapsible sectional forms arranged between said continuous forms and projecting above them for supporting the floor, the ends of successive sectional forms overlapping each other at the joists, means carried by said joists for supporting said sectional forms above the level of the joists, and means for preventing collapse of said sectional forms, said supporting means and means for preventing collapse being arranged to permit said sectional forms to be telescoped one within the next whereby they may be withdrawn without disturbing the joist and continuous forms.

9. Apparatus for constructing ribbed concrete floors which comprises joists extending crosswise of the ribs beneath their under sides for supporting them, forms for the ribs supported on said joists, sectional floor forms between said rib forms, and removable members on said joists for supporting said sectional forms above the level of the joists, the ends of successive sectional forms overlapping each other at the joists, whereby said sectional forms may be removed and said joists and rib forms left in place to support the floor.

Signed at St. Louis, Missouri, this 19th day of February, 1917.

ARTHUR J. WIDMER.
